UNITED STATES PATENT OFFICE.

ERNEST H. BENNETT, OF EAST ORANGE, NEW JERSEY, ASSIGNOR TO JOHN H. BROMLEY AND EDWARD BROMLEY, COPARTNERS TRADING AS JOHN BROMLEY & SONS, OF PHILADELPHIA, PENNSYLVANIA.

DESIGN FOR A RUG.

SPECIFICATION forming part of Design No. 35,934, dated June 3, 1902.

Application filed April 30, 1902. Serial No. 105,409. Term of patent 3½ years.

To all whom it may concern:

Be it known that I, ERNEST H. BENNETT, a citizen of the United States, residing at East Orange, New Jersey, have invented and produced a certain new and original Design for a Rug, of which the following is a full, clear, and exact description, reference being had to the accompanying drawing, forming a part of this specification.

My invention relates to the surface ornamentation of a woven rug; and it consists of the design therefor shown in said drawing, which represents a rug design of rectangular outline, the leading and distinguishing features of which are the double-line border formed by the parallel small line-figures *a* and *b*, between which is a series of arabesque figures *c*. The field center is filled in with a diamond-shaped figure in outline (marked *d*) com-

posed of numerous small line and arabesque figures, while at each end of the field center are like angularly-disposed figures *e e*, pointing outward and in opposite directions to each other, each of the four corner-spaces formed thereby being filled in with small figures, (indicated by the letter *e'* on the drawing.)

Having thus described my invention, what I claim as new, and desire to secure by Letters Patent, is—

The design for a rug, substantially as shown and described.

In testimony whereof I have hereunto affixed my signature this 6th day of December, A. D. 1901.

ERNEST H. BENNETT.
